UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

BOSOM-BOARD.

1,072,808.

Specification of Letters Patent. Patented Sept. 9, 1913.

Application filed June 15, 1910. Serial No. 567,026.

To all whom it may concern:

Be it known that I, WILLIAM BARTHOLOMEW, a citizen of the United States, residing at Chicago, county of Cook, State of Illinois, have invented certain new and useful Improvements in Bosom-Boards, of which the following is a specification, reference being had therein to the accompanying drawing.

10 This invention relates to a bosom board and particularly to means for retaining a shirt or garment thereon and for stretching it preparatory to an ironing operation.

The invention has for an object to provide 15 a novel and improved construction and mounting of the bosom board and also of the means for clamping the clothing thereon.

A further object of the invention is to provide a novel construction of neck-band 20 clamp and also of yoke clamps by which the upper portion of a shirt is retained in proper position upon the board for ironing purposes.

Another object of the invention is to provide 25 a novel construction of stretching device adapted to stretch either side of a shirt independently of the other by contact with the tail thereof.

Other and further objects and advantages 30 of the invention will be hereinafter set forth and the novel features thereof defined by the appended claims.

In the drawings—Figure 1 is a plan of 35 the bosom board; Fig. 2 is a side elevation thereof with parts in section; Fig. 3 is a detail vertical section showing the clamping of the clothing upon the board; Fig. 4 is an enlarged plan of the clothing and neck band clamps; Fig. 5 is a vertical section showing 40 one of the yoke clamps; Fig. 6 is a plan of these clamps with parts in section; Fig. 7 is a detail section on line 7—7 of Fig. 6; Fig. 8 is a detail elevation of the face of one of the yoke clamps; Fig. 9 is a vertical section through the holding means for the 45 stretching bars; Fig. 10 is a plan of this means with parts in section; Fig. 11 is a section on line 11—11 of Fig. 9; Fig. 12 is a section on line 12—12 of Fig. 1; Fig. 13 is a detail elevation of a yoke clamp; Fig. 14 is a plan of a modified application of the neck band clamp; Fig. 15 is a similar view of a modified form of this clamp; Fig. 16 is a

section on line 16—16 of Fig. 15; and Fig. 17 is a detail face view of the neck band 55 clamp.

Like numerals of reference refer to like parts in the several figures of the drawings.

The numeral 10 designates the base plate of the board which is provided at opposite 60 ends and at each side with attaching plates 11 by which it may be mounted upon any suitable part of an ironing machine. This plate is provided with a series of ribs 12 extending from the board support 13 at the 65 center thereof to the ends of the plate. Upon this support, the segmental ironing board 14 is mounted and the centrally disposed depending portion 15 thereof rests upon the support 13 and is retained against 70 rotative movement by means of pins or posts 16 threaded into the support 13 and extending through unthreaded apertures 17 in the portion 15. The board and base are secured against vertical movement by means 75 of a bolt 18 threaded into the portion 15 and this bolt permits the ready separation of the parts.

The board 14 is covered by the usual fabric clothing 19 which is held in position 80 thereon in any desired manner at the sides and ends of the board. The clothing at the neck band portion is, however, clamped into position by a yoke 20 which is pivotally mounted upon the board at 21 by means of 85 depending lugs 22. The yoke 20 is substantially segmental in shape and conforms to the configuration of the neck band portion 23 of the board. The yoke is also provided with a frame 24 formed with a spring clip 90 25 adapted to engage a pin 26 secured to the board, similar to the clip 87 and pin 88 shown in Fig. 17.

Upon the frame 24, pivoting standards 95 27 are mounted and have pivoted therein a rock shaft 28 provided with a crank arm 29 by which the neck band clamp 30 is actuated. This clamp is formed with slots 31 which embrace screws 32 mounted in the frame 24 and provide for a sliding 100 movement of the clamp toward and from the clothing clamp. The neck band clamp may be actuated from the crank arm 29 in any desired manner, for instance by means of a link 33 pivotally mounted in lugs 34 105 upon the clamping plate 30 and slidingly

mounted at its opposite end in the socket 35 pivoted at 36 to the arm 29. The link 33 is provided with a cross pin 37 which slides in the slots 38 formed in the socket 35. The link is also surrounded by a tension spring 39 which bears at one end against the socket 35 and at its opposite end contacts with a bearing 40 upon the link. This construction gives a yielding pressure of the neck band clamp upon the goods held thereby to prevent injury thereto. The segmental face 41 of the clamp 30 may be corrugated as shown in Fig. 3 to secure a proper frictional hold upon the 10 clothing and the rock shaft 28 may be provided with a handle 42 secured thereto by which it can be operated.

Upon the end 43 of the base 10, oppositely disposed yoke clamps 44 are mounted, these being capable of joint or independent 20 operation. Each clamp is provided with a laterally disposed holding face 45 which, if desired, may be of felt or roughened. These yoke clamps are provided with a 25 tubular hub 46 mounted upon a bearing rod 47, this rod being pivoted in bearings 48 carried by a frame 49 which is secured to the extended portion 43 of the base in any desired manner. Each bearing 46 has secured thereto an extended arm 50 provided with a handle 51 by which it may be operated. The tubular hubs 46 are secured to the shaft 47 by means of set-screws 52 as shown in Figs. 6 and 7 so that when 30 both hubs are secured to the shaft, the clamps are operated in unison; but by releasing their set screws, the yoke clamps may be independently operated. These clamps are normally held in contact with the end 35 of the bosom board by tension means, a desirable form thereof being a crank arm 53 carried by the hub 46 and having pivoted thereto a sliding pin 54 which, at its opposite end, extends through a bearing 55 which is pivotally mounted at 56 in the lugs 57 carried by the frame 49. This pin is formed with a shoulder 58 and is surrounded by a coiled spring 59 which bears against said shoulder and also against the 45 bearing 55. The tension means just described is duplicated for the independent yoke clamps so that if one is disconnected from the other, it will be held under tension.

55 For the purpose of stretching the shirt or other garment upon the board, a stretching bar is provided at the tail of the board. This bar is preferably composed of separate sections 60, one at each side of the 60 center of the board and formed rectangular in cross section so that when a portion of the shirt is wound thereon, it will be frictionally held. As shown in Fig. 12, the sections 60 are mounted upon a tube 61 which has its bearing upon a shaft 62 and

these sections are separated by a collar 63 secured to said shaft. The shaft 62 is continuous through both of the stretcher bar sections. The bearing tubes 61 are provided at their outer ends with ratchets 64 inclosed within protecting casings 65. These casings are supported by a bracket 66 secured at 67 to the opposite sides of the board 14 at one end thereof. For the purpose of retaining the ratchet 64 and the roll section carried thereby, a sliding pawl 68 is provided. This pawl is mounted upon a base plate 69 and held in position by screws 70 passing through slots 71 in the pawl and entering the base plate 69. When it is desired to release the pawl in the removal of goods from the bosom board, this may be accomplished by a trigger lever 72 which is pivoted at 73 within an aperture in the bracket 66 and the upper end 74 thereof passes through the pawl plate 68 so as to shift the pawl in the movement of the lever 72. This lever and pawl are normally held in position to engage the ratchet by means of the tension spring 75 disposed in a recess 76 in the base plate 69 to engage the upper end 74 of the lever 72.

In Fig. 14, a modified application of the neck band clamp is shown and comprises the use of two clamps disposed at opposite sides of the longitudinal center of the ironing board 14. This form of the invention is particularly adapted for ironing open front shirts as it permits the edges to be separated and properly ironed while 100 clamping each side in relative position. The form of neck band clamp shown in Fig. 14 is substantially that disclosed in Figs. 15 and 16 and the operating means for each of the clamps is connected by a 105 rod 80 with a crank arm 81 carried by a rock shaft 82 provided with an operating handle 83 and disposed upon the under side of the ironing board as shown by dotted lines in Fig. 14. This permits the 110 operation of the clamps from a side of the board.

The modified form of clothing clamp and neck band clamp shown in Figs. 15 and 16 comprises substantially a reversal of the 115 yielding link construction shown in Figs. 3 and 4. In Fig. 15, the yoke 84 clamps the clothing in position and is provided with a supporting frame 85 upon which the neck band clamp is slidingly mounted. This yoke 120 may be pivotally mounted upon the board by means of the pivot screws 86 at opposite sides and is provided upon its under face with a spring clip comprising opposite jaws 87 adapted to engage a pin or projection 88 125 as shown in Fig. 17. These parts are substantially similar to the spring clip 25 shown in Figs. 2 and 3. The neck band clamp 89 is provided with a contact face 90 to engage the article upon the board and is slidingly 130

mounted by means of the slots 91 therein through which the retaining screws 92 pass and enter the frame 85. This frame is provided with pivoting lugs 93 and 94 in which a rock shaft 95 is mounted. This shaft has a crank arm 96 secured thereto and also an operating handle 97. A link 98 is pivotally mounted upon a pin 99 extending from this crank arm and the opposite end of the link is disposed within a socket 100 which is pivotally supported in the lugs 101 carried by the neck band clamp 89. The socket is provided with an elongated slot 102 within which a pin 103 carried by the link travels as shown in Fig. 3. Surrounding the link and bearing against the socket, is a tension spring 104 by which the face of the neck band clamp is held in yielding contact with the goods and under constant tension.

In the operation of the invention, the shirt or other garment to be ironed is placed upon the board and the neck band clamp brought into engagement therewith to retain the shirt in the usual manner while the yoke or shoulder clamps are also engaged by actuating their controlling lever. The tail or lower portion of the shirt is then wound upon the stretcher bar and the sections thereof rotated to tightly draw the bosom of the shirt into contact with the board. The construction of this bar in sections permits an independent stretching of the sides of the shirt so as to compensate for any slack which may occur and also any slipping of the garment when wound upon the bar sections and thus insure a tighter and closer fit of the shirt upon the board. The neck band clamp is adapted for rapid operation by means of the lever and yielding connection which also prevents injury to the goods. The yoke clamps are also yieldingly held and are mounted for independent movement or simultaneous movement in clamping the shoulders of the shirt upon the board. This permits the shirt to be adjusted after one of the clamps has been placed in position so as to take up any lateral looseness which may occur. The clothing upon the board is clamped in position by the yoke and can be readily released whenever it is desired to change or remove it. The sections of the stretcher bar are automatically retained in their adjusted positions by the pawl and ratchet and may be released instantly through the trigger lever connection. It will therefore be seen that the invention presents a simple and very efficient construction of bosom board with clamps for the clothing thereof, the neck band of the article ironed, and the shoulders thereof together with means for stretching such an article in a direction away from the clamping devices. The ironing board is also mounted upon the base plate so that it can

be readily removed and when in position is held against rotary or lateral movement by the pins passing therethrough.

Having described my invention and set forth its merits what I claim and desire to secure by Letters Patent is—

1. In an ironing board, a bosom board provided with a segmental neck portion, clothing disposed upon said bosom board, a pivoted yoke disposed within said neck portion to retain said clothing in position, and an independent neck band clamp.

2. In an ironing board, a bosom board provided with a segmental neck portion, clothing disposed upon said bosom board, a pivoted yoke disposed within said neck portion to retain said clothing in position, an independent neck band clamp and a support extended from the bosom board to engage said yoke.

3. In an ironing board, a bosom board provided with a segmental neck portion, clothing disposed upon said bosom board, a pivoted yoke disposed within said neck portion to retain said clothing in position, an independent neck band clamp, and a supporting pin secured to said bosom board to engage a spring on said yoke in the downward movement thereof.

4. In an ironing board, a bosom board provided with a segmental neck portion, clothing disposed upon said bosom board, a pivoted yoke disposed within said neck portion to retain said clothing in position, and a neck band clamp mounted upon the frame of said yoke to travel therewith and for sliding movement thereon.

5. In an ironing board, a bosom board provided with a segmental neck portion, clothing disposed upon said bosom board, a pivoted yoke disposed within said neck portion to retain said clothing in position, a neck band clamp slidably mounted upon the frame of said yoke to engage the inner face thereof, means upon said yoke for actuating said clamp, shoulder clamps disposed at opposite sides of said yoke, and stretching means carried by said bosom board at its end opposite said yoke.

6. In a bosom board, a neck band clamp comprising a slotted sliding plate having a clamping face, a frame provided with a supporting face, means extending through the slot of said plate and mounted upon said frame, a rock shaft pivoted upon said frame and provided with operating means, a crank arm carried by said rock shaft, and a connection pivoted to said arm and plate.

7. In a bosom board, a neck band clamp comprising a slotted plate having a clamping face, a frame provided with a supporting face, means extending through the slot of said plate and mounted upon said frame, a rock shaft pivoted upon said frame and provided with operating means, a crank arm

- carried by said rock shaft, and a yielding connection pivoted to said arm and plate.
8. In a bosom board, a neck band clamp comprising a slotted plate having a clamping face, a frame provided with a supporting face, means extending through the slot of said plate and mounted upon said frame, a rock shaft pivoted upon said frame and provided with operating means, a crank arm carried by said rock shaft, a yielding connection pivoted to said arm and plate, and means for pivotally mounting said frame upon said board.
9. In a bosom board, a plurality of yoke clamps, a supporting shaft upon which they are pivotally mounted, independent tension means for moving each clamp in one direction, and means for detachably connecting one of said clamps to said shaft.
10. In a bosom board, a plurality of yoke clamps, a supporting shaft upon which they are pivotally mounted, independent tension means for moving each clamp in one direction, means for detachably connecting each of said clamps to said shaft, and means carried by each clamp for moving it in opposition to said tension means.
11. In a bosom board, a plurality of yoke clamps, a supporting shaft upon which they are pivotally mounted, independent tension means for moving each clamp in one direction, means for detachably connecting each of said clamps to said shaft, an arm extended from the hub of each of said clamps, and a handle carried by each of said arms.
12. In a bosom board, a supporting frame provided with bearings, a shaft mounted in said bearings, a plurality of yoke clamps independently mounted upon said shaft and provided at their hubs with a crank arm, independent tension means bearing upon said frame and connected to the crank arm of each clamp, and means for connecting either clamp to said shaft.
13. In a bosom board, a supporting frame provided with bearings, a shaft mounted in said bearings, a plurality of yoke clamps independently mounted upon said shaft and provided at their hubs with a crank arm, independent tension means bearing upon said frame and connected to the crank arm of each clamp, and a set screw mounted in the hub of one of said clamps to engage said shaft.
14. In a bosom board, a supporting frame provided with bearings, a shaft mounted in said bearings, a plurality of yoke clamps independently mounted upon said shaft and provided at their hubs with a crank arm, independent tension means bearing upon said frame and connected to the crank arm of each clamp, and an operating handle carried by the hub of each of said clamps.
15. In a bosom board, supporting brackets at one end thereof, a shaft mounted in said
- brackets, independently rotatable stretcher bar sections mounted upon said shaft, and means for retaining each of said sections in adjusted position.
16. In a bosom board, supporting brackets at one end thereof, a shaft mounted in said brackets, independently rotatable stretcher bar sections mounted upon said shaft, means for retaining each of said sections in adjusted position, and means for independently releasing said retaining means.
17. In a bosom board, supporting brackets at one end thereof, a shaft mounted in said brackets, independently rotatable stretcher bar sections mounted upon said shaft, a retaining ratchet carried by each of the stretcher bar sections, a spring pawl mounted to engage each ratchet, and a lever mounted to retract each pawl.
18. In a bosom board, supporting brackets at each end thereof, a shaft mounted in said brackets, independently rotatable stretcher bar sections mounted upon said shaft, a retaining ratchet carried by each of the stretcher bar sections, a sliding pawl mounted to engage each of said ratchets, a lever mounted to retract said pawl, and a tension spring for moving said pawl and lever to engage the former with said ratchet.
19. In a bosom board, supports provided at one end thereof, a shaft mounted in said supports, independent stretcher bar sections, tubes secured to said sections and mounted upon said shaft, and retaining means carried by the outer end of each tube.
20. In a bosom board, supports provided at one end thereof, a shaft mounted in said supports, independent stretcher bar sections, tubes secured to said sections and mounted upon said shaft, retaining means carried by the outer end of each tube, a collar secured to said shaft intermediate the bar sections, and inclosing casings carried by the supports to receive said retaining means.
21. In an ironing board, a rotatably mounted sectional stretcher bar supported at one end thereof, a ratchet carried by each section of said bar, a co-acting sliding pawl for each ratchet, and a retracting lever pivotally mounted beneath each pawl and extending therethrough.
22. An ironing board having a revolvably mounted stretcher bar at one end thereof, formed of two sections in alignment, a ratchet carried by each section thereof, a sliding pawl to engage each ratchet, a retracting lever pivoted beneath each pawl and extending therethrough, and a tension spring disposed in a recess beneath each pawl and engaging the upper end of said lever.
23. In an ironing board, a rotatably mounted sectional stretcher bar supported at one end thereof, a ratchet carried by each section of said bar, a sliding pawl to engage

each of said ratchets, a retracting lever pivoted beneath each of said pawls and extending therethrough, a tension spring disposed in a recess beneath each of said pawls 5 and engaging the upper end of each of said levers, and a holding screw extending through a slot formed in each of said pawls.

24. The combination with a bosom board, clamping means for retaining an article at 10 one end thereof, stretching means disposed transversely at the opposite end and comprising independently rotatable sections and means for retaining the article in stretched position upon said board.

15 25. In a bosom board, a clothing clamp pivotally mounted at the neck band portion thereon, and a movable neck band clamp mounted thereon and having tension means

to hold it in engagement with the inner face of the clothing clamp.

26. In a bosom board, a neck band clamp comprising a sliding plate having a contact face, a crank shaft for operating said plate, a link pivotally connected to one of said parts, a socket pivoted to the other part to 25 receive the free end of said link, a tension spring disposed between said socket and link, and a pin carried by said link and mounted to travel in slots in said socket.

In testimony whereof I affix my signature 30 in presence of two witnesses.

WILLIAM BARTHOLOMEW.
